UNITED STATES PATENT OFFICE

JAMES GRAYSON LUTTRELL, OF BALTIMORE, MARYLAND, ASSIGNOR TO McCORMICK & CO., INCORPORATED, OF BALTIMORE, MARYLAND, A CORPORATION OF MARYLAND

DESIGN FOR A COUNTER SERVICE TEAPOT

Application filed November 30, 1932. Serial No. 46,205. Term of patent 7 years.

To all whom it may concern:

Be it known that I, JAMES GRAYSON LUTTRELL, a citizen of the United States, residing at Baltimore, in the county of Baltimore and State of Maryland, have invented a new, original, and ornamental Design for a Counter Service Teapot, of which the following is a specification, reference being had to the accompanying drawing constituting a part thereof.

In the drawing:—

Fig. 1 is a perspective view of the counter service teapot showing my new design.

Fig. 2 is a front elevation thereof.

I claim:

The ornamental design for a counter service teapot, substantially as shown.

In testimony whereof I have hereunto subscribed my name this 28 day of November, 1932.

J. GRAYSON LUTTRELL.
